BERNEY KNUDSEN, OF DENVER, COLORADO, ASSIGNOR OF ONE-HALF TO F. G. WARRICK,
OF SCOTTSBLUFF, NEBRASKA.

SANITARY CAN-TAP.

1,277,222.

Specification of Letters Patent. Patented Aug. 27, 1918.

Application filed December 14, 1916. Serial No. 136,983.

To all whom it may concern:

Be it known that I, BERNEY KNUDSEN, a citizen of the United States, residing at Denver, in the county of Denver and State 5 of Colorado, have invented certain new and useful Improvements in Sanitary Can-Taps; and I do hereby declare the following to be a full, clear, and exact description of the invention, such as will enable others skilled 10 in the art to which it appertains to make and use the same.

This invention relates to a sanitary can tap and has for its principal object to provide a device of this character whereby a 15 metal can may be readily and quickly tapped in order that the contents may be removed as desired.

Another object of the invention is the provision of a device of the above stated character 20 embodying a handle shank having a pointed end, and a hollow bit detachably mounted upon the shank and adapted to be tapped into a metal can top in such a manner as to provide an air tight connection 25 between the bit and can top, said shank designed to be removed immediately after the bit has been arranged in position and a closure cap adapted to be positioned over the end of the hollow bit.

30 A further object of the invention is the provision of a hollow bit adapted to be reversibly mounted upon the handle shank, and a closure cap provided for one end of the hollow bit, said cap serving in one instance 35 as a closure for the hollow bit when attached to a metal can top, and in the other instance serving as a protector cap for the pointed end of the handle shank when the device is reassembled for commercial handling.

40 A still further object of the invention is to provide a handle shank with a non-circular portion and a flange, said non-circular portion designed to engage a similar opening in the end of a hollow bit whereby the 45 bit will be caused to rotate with the handle shank, said non-circular portion and flange also serving to prevent the handle shank from being inserted through the hollow bit too far.

50 With these and other objects in view as will appear as the description proceeds, the invention comprises the various novel features of construction, combination and arrangement of parts as will be more fully

described hereinafter and set forth with 55 particularity in the appended claims.

Referring to the drawings,

Figure 1 is a side elevation of my improved sanitary can tap assembled and arranged in position for commercial handling. 60

Fig. 2 is a sectional elevation showing the various parts reassembled into operative position and tapped through a metal can top.

Fig. 3 is a detail perspective view of the 65 hollow bit.

Fig. 4 is a detail perspective view of the closure cap for said bit.

Fig. 5 is a detail perspective view of a can showing the hollow bit tapped through the 70 top thereof and the closure cap arranged in position upon the upper end of the bit.

Similar characters of reference are used to denote like parts throughout the accompanying drawings and the following description. 75

Referring more particularly to the drawings the reference numeral 1 indicates the shank of my improved sanitary can tap, one end of which is extended and bent to form a handle loop 2, which may be of any 80 design and formation found most desirable and best suited for the purpose. The opposite end of the shank 1 is provided with a tapered point 3 in order to facilitate easy and ready insertion of the point through a 85 piece of metal such as a metal can top or the like. The shank 1 is further provided intermediate its ends with a non-circular portion 4 and a flange 5 which is arranged immediately above the non-circular portion 90 4 as clearly shown in Figs. 1 and 2 of the drawings.

The reference numeral 6 indicates an improved form of a hollow bit which is shown to consist of a sleeve 7, the outer surface of 95 which is slightly tapered as clearly indicated in Fig. 3. The upper end portion of the sleeve is formed internally non-circular and is designed to receive the non-circular portion 4 of the shank 1 when the latter is inserted through the bit. The lower end of the sleeve 7 is provided with a circular flange 8 that is reinforced upon its upper side by a slightly enlarged portion 9. The underneath surface of the flange 8 is dished as indicated by the numeral 10 for a purpose 100 which will presently appear.

The lower end of the sleeve 7 or that por-

tion of the sleeve that is disposed below the flange 8 is provided externally with sharp edge screw threads 11 to form a hollow screw bit. The upper terminal end portion 5 of each of these screw threads 11 terminates at points in spaced relation to the dished under surface 10 of the flange 8 so as to provide a space of sufficient width to receive the thickness of the metal forming the can 10 top, as clearly shown in Fig. 2 of the drawings.

When it is desired to tap a metal can top, it is simply necessary to assemble the parts as shown in Fig. 2 of the drawings and then 15 insert the point 3 through the can top, after which the handle 2 is rotated and screwed under pressure until the sharp threads 11 have cut their way through the top. When the hollow bit has been rotated 20 until it is tight with the can top it will be so securely tapped through and attached to the metal can top as to provide a non-leakable joint between the bit and can top. As soon as the hollow bit has been arranged in 25 position, the handle and shank are removed from the bit thus leaving the hollow bit to serve as a tap whereby the contents of the can may be readily poured therefrom as desired.

30 In order to prevent the contents of the metal can from evaporating or to exclude dirt or any other foreign substance therefrom, I provide a metal closure cap 12, shown in Fig. 4, which is of substantially 35 cylindrical shape and is formed to provide tapering walls 13 that are designed to frictionally engage over and with the tapered outer surface of the sleeve 7, as clearly shown in Fig. 5 of the drawings. This cap 40 12 serves as a double purpose, and in the first instance is used as a protector cap for the pointed end of the shank 1. In order to be subjected to this use, the hollow bit 6 is reversibly mounted upon the shank as 45 clearly shown in Fig. 1 of the drawings, the cap 12 being frictionally mounted upon the end of the sleeve 7 so as to entirely and completely inclose the pointed end of the shank, which arrangement is found desirable 50 in commercially handling the device. Secondly, the closure cap is used to seal the can by being placed frictionally over the top of the tapered sleeve 7.

From the foregoing it will be apparent 55 that I have provided a novel form of sanitary can tap which may be readily and quickly applied to a can.

What I claim is:—

1. A can tap comprising a handle, a 60 shank extending from said handle and provided with a pointed end, a hollow bit adapted to be attached to said shank, and a protector cap adapted to be attached to said bit.

65 2. A can tap comprising a handle, a shank

extending from said handle and formed with a pointed end, a hollow bit slidably mounted upon said shank, and means to fix said hollow bit to said shank.

3. A can tap comprising a handle, a shank 70 extending from said handle and formed with a pointed end, a non-circular portion formed on said shank intermediate its ends, and a hollow bit slidably mounted upon said shank and formed internally at one end with 75 a non-circular opening adapted to receive the non-circular portion of said shank whereby the hollow bit will be caused to rotate with the shank.

4. A can tap comprising a handle, a shank 80 projecting from said handle and formed with a pointed end, a non-circular portion formed on said shank intermediate its ends, a hollow bit slidably mounted upon said shank and formed internally at one end 85 with a non-circular opening adapted to receive the non-circular portion of said shank, and means carried by the shank adapted to limit the sliding movement of the hollow bit upon said shank.

5. A can tap comprising a handle, a shank 90 projecting from said handle and formed with a pointed end, a hollow bit slidably mounted upon said shank and adapted to be reversibly mounted thereon end for end, 95 means for locking the hollow bit to said shank for rotation therewith, and means carried by said shank and adapted to prevent sliding movement of the bit in one direction upon said shank.

6. The combination with a metallic can, 100 of a sanitary can tap comprising a handle, a shank extending from said handle and formed with a pointed end, a hollow bit detachably mounted upon said shank, means 105 to lock said bit to the shank for rotation therewith, a flange formed on the hollow bit, and a hollow screw formed integral with said flange and adapted to be threaded through the can top and said shank removed 110 therefrom to provide a tap for said can, and a closure cap for said hollow bit.

7. A can tap comprising a handle, a shank 115 extending therefrom and formed with a pointed end, a hollow bit detachably mounted on the outer end of said shank and comprising a sleeve, a flange formed on the sleeve, edge screw threads formed on the sleeve between said flange and the end of the sleeve, means to limit the inward movement 120 of the bit on the shank so that the outer end of the screw threaded sleeve will lie adjacent the pointed shank end, and means for keying the bit to said shank.

8. In a device of the class described, the 125 combination with the pointed shank thereof, of a hollow bit detachably mounted on the outer end of said shank and comprising a sleeve, a flange formed on said sleeve, sharp-edge screw threads formed on the 130

5 sleeve between the outer end and said flange, said sharp-edge screw threads gradually increasing in diameter from the sleeve end to said flange, and means to lock the bit to the shank, the bit being so positioned upon the shank that the said screw threads and pointed shank end form a conical inserting end.

9. In a device of the class described, the 10 combination with the pointed handle shank thereof, of a hollow bit detachably mounted on the outer end of said shank and comprising a sleeve, a flange formed on said sleeve, sharp-edge screw threads formed on the 15 sleeve between the outer end and said flange, the inner terminal ends of said threads terminating in spaced relation to said flange, and means to lock the bit sleeve to the shank.

10. In a device of the class described, the

combination with the pointed handle shank 20 thereof, of a hollow bit detachably mounted on the outer end of said shank and comprising a sleeve, a flange formed on said sleeve, said flange formed with a dished outer surface, sharp-edge screw threads 25 formed on the sleeve between the outer end and said flange, the inner ends of said screw threads terminating in spaced parallel relation to the dished surface of said flange, and means to lock the bit sleeve to said 30 shank.

In testimony whereof I have signed my name to this specification in the presence of two subscribing witnesses.

BERNEY KNUDSEN.
